Primary Examiner — Brandon M Rosati*Assistant Examiner* — Rhea Shields*(74) Attorney, Agent, or Firm* — Cantor Colburn LLP(57) **CLAIM**

The ornamental design for a display screen or portion thereof with icon, as shown and described.

DESCRIPTION

FIG. 1 is a front view of a display screen or portion thereof with icon showing our new design;

FIG. 2 is a second embodiment thereof; and,

FIG. 3 is a third embodiment thereof.

The broken lines illustrating portions of the display screen or portion thereof with icon are for environmental purposes only and form no part of the claimed design. It should be appreciated that at least a portion of the display screen is shown inside the broken lines.
